THE NORRIS PETERS CO., SHOT & LITHO., WASHINGTON, D. C.

UNITED STATES PATENT OFFICE.

GEORGE MARTINSEN, OF CLEVELAND, OHIO.

SNIPE.

1,127,791.

Specification of Letters Patent.

Patented Feb. 9, 1915.

Application filed March 4, 1914. Serial No. 822,375.

To all whom it may concern:

Be it known that I, GEORGE MARTINSEN, a subject of the King of Norway, residing at Cleveland, in the county of Cuyahoga and 5 the State of Ohio, have invented a new and useful Improvement in Snipes, of which the following is a specification.

This invention relates to a snipe adapted to be rigidly secured upon a suitable bench 10 and provided with an operating lever by means of which the jaws may be thrown into closed or cutting position from either side of the bench.

The invention consists of the novel features of construction hereinafter described, 15 pointed out in the claims and shown in the accompanying drawings, in which,

Figure 1 is a side elevation of the device, 20 the operating lever and jaws being shown in full lines in one of the closed positions, the lever being shown in the dotted lines, with the jaws in closed position in full lines and the jaws and operating lever being shown in open position in dotted lines. Fig. 2 is a 25 section on the line 2—2 of Fig. 1. Fig. 3 is a section on the line 3—3 of Fig. 2. Fig. 4 is a detail perspective view of a wedging strip.

In these drawings, 1 represents a suitable 30 standard having a reduced portion 2 adapted to fit into the rectangular opening of a work bench and carrying a depending threaded portion 3 upon which works a suitable clamping washer 4 and nut 5. The upper 35 portion of the standard is provided with a dovetailed slot 6. Cutting jaws 7 and 8 are provided with suitable pivoted intersecting handles 9 and 10. The jaw 8 is provided with a downwardly extending lug 11 the 40 lower edge of which is provided with a longitudinally extending tongue 12 adapted to fit within the dovetailed groove 6. In order to firmly wedge and lock the tongue in said groove and at the same time not mar the 45 tool, I provide a wedging strip 13 which is adapted to fit in the groove parallel with the tongue, and against which presses the inner end of a set screw 14. The strip 13 is provided with laterally bent end portions 15 50 longitudinally slotted as shown at 16 through which work suitable adjusting

screws 17, the slots permitting lateral adjustment or movement of the strip 13, and said strip having also a limited longitudinal movement. An operating lever 18 is pivotally connected to the handle 9 of the jaw 8, this being the fixed jaw. The handle 10 of the movable jaw 7 is obliquely cut away at its rear end as shown at 19 and forms a bearing for the lever 18 when the jaws are 60 in closed position and are operated from the rear. A link 20 is pivotally connected to the inner end of the lever 18 and is also pivotally connected to the handle 10 thereby transmitting movement of the lever 18 to 65 the jaw 7. By throwing the lever into the position shown by broken lines *a* in Fig. 1 the jaw 7 will be moved into open position. By throwing the lever forward into the position shown by dotted lines *b* in Fig. 1 70 the jaw 7 will be closed so that there are two closing movements of the jaw for one full swing of the lever, and the device can be operated by means of the lever from either the front or rear side of the bench or table 75 upon which it may be arranged.

What I claim is:—

1. A device of the kind described comprising a grooved standard, pivoted jaws, a lug carried by one of said jaws, said lug being adapted to coöperate with said groove, a wedging strip adapted to fit in said groove and to bear on the coöperating portion of said lug, and means for limiting longitudinal movement of the wedging strip. 85

2. The combination with a pair of jaws, a rigid support for one of said jaws, said jaws being provided with handles, a lever pivoted upon the handle of the jaw having the support, the other handle having its 90 end cut obliquely to furnish a support for said lever, and a link pivotally connected to the obliquely cut handle and to the lever, said jaws being closed when the lever is at the end of its swinging movement in 95 either direction and being open when the lever is in an intermediate position.

GEO. MARTINSEN.
